ELECTRON DISCHARGE TUBE HIGH-FREQUENCY AMPLIFIER AND MODULATING CIRCUITS THEREFOR

Victor James Cooper, Writtle, and Ernest Green, Writtle, Chelmsford, England, assignors, by mesne assignments, to Radio Corporation of America, New York, N. Y., a corporation of Delaware

Application October 24, 1946, Serial No. 705,264
In Great Britain December 5, 1945

4 Claims. (Cl. 332—24)

1

The invention relates to electron discharge tube high frequency amplifiers and modulating circuits therefor.

A difficulty which commonly arises in radio frequency amplifiers of the grid modulated type is that the grid current taken by the amplifier tube or tubes is not a rectilinear function of the input and since this current constitutes a load upon the radio frequency excitation stage driving the amplifier, the amplitude of excitation is likely to vary with variation of grid current consequent upon variation of modulating voltage. A known expedient for avoiding or reducing this disadvantage is to provide additional grid loading resistance for the driver stage so as to reduce the percentage load variation caused by grid current variation. This expedient, however, is wasteful of power imposing an extra load upon the driving stage.

The object of the present invention is to avoid or reduce the above mentioned disadvantage without incurring the substantial power wastage of the known expedient just described.

According to this invention a radio frequency amplifier is excited from a radio frequency exciter source through at least one stage to which said amplifier is in so-called "cathode follower" coupling relation, the said stage being thus arranged with respect to the amplifier as though it were a very low resistance generator whereby the defect above mentioned is reduced or avoided.

Modulating input may be applied in any convenient manner known per se to the driven radio frequency amplifier. Owing, however, to the well known inherent wide-band properties of the cathode follower type of connection, the invention lends itself to the application of modulation input at the point of lower power level constituted by the input to the stage to which the radio frequency amplifier is cathode-follower-coupled with obvious advantages as regards loading of the modulator.

The invention is illustrated in the accompanying drawings which show diagrammatically several embodiments.

Referring to Fig. 1, a radio frequency exciter source is connected between the control grids G₁G₂ of a cathode follower stage comprising tubes V₁V₂, the usual radio frequency tuned circuit L₁C₁ with earthed centre point P being connected between the grids. Each grid G₁G₂ is cross-connected to the cathode K₁ or K₂ respectively of the other tube through a neutralising condenser C₃ or C₄ respectively, which balance out grid-cathode capacities, and the two cathodes are connected

2

together through a tuned circuit C₂L₂ constituting the cathode leg impedance. The anodes A₁A₂ are earthed through condensers AC₁AC₂ and receive anode potential from a common source (not shown). Voltage developed between the ends of the cathode leg impedance C₂L₂ is applied to the succeeding driven radio frequency amplifier stage which may be arranged in various different ways. For example, as shown in Fig. 1, it comprises two tubes V₃V₄ with their cathodes K₃K₄ earthed and their grids G₃G₄ capacity-coupled by condensers C₅C₆ each to one end of the cathode leg impedance C₂L₂. Modulator output from a suitable modulator is applied to the junction point of two chokes L₃L₄ connected between the grids G₃G₄. Output to a load is taken from across an output tuned circuit C₈L₅ connected between the anodes A₃A₄, anode potential being applied through the midpoint of coil L₅ from a potential source (not shown). Neutralisation of the grid-anode capacities of the driven stage amplifier tubes V₃V₄ is effected by cross-connecting the tube grids G₃G₄ through neutralizing condensers C₇C₈ to the anodes A₄A₃.

10 In the modification shown in Fig. 2, the amplifier tube grids G₃G₄ are connected to opposite ends of a neutralising impedance N having a center tap CT to which the modulator is connected, the cathodes being connected together through chokes L₃L₄ in positions vis-a-vis the preceding stage, corresponding to those of chokes L₃L₄ of Fig. 1. Thus it will be seen that Fig. 2 incorporates a grounded grid, grid modulated amplifier.

20 Fig. 3 shows a third embodiment which differs from Fig. 1 in that the output tuned circuit C₈L₅ from which the load is fed is connected between the cathodes K₃K₄ instead of between the anodes A₃A₄, the neutralising condensers C₇C₈ being in this case cross-connected between the grids G₃G₄ and the cathodes K₄K₃ of the tubes V₃V₄. Thus the amplifier is also in cathode follower coupling relation with the load.

25 If desired, modulation may be effected at the input circuit of the stage preceding the amplifier. Thus the embodiment illustrated in Fig. 4 differs from Fig. 1 only in that the modulator is connected to the center tap P on the coil of the circuit L₁C₁ between the grids G₁G₂ of the tubes V₁V₂. Similarly, the embodiment of Fig. 5 resembles that of Fig. 2, the only difference being that the modulator is connected as in Fig. 4. Again, the embodiment of Fig. 6 differs from that of Fig. 3 only in that the modulator connection is

taken to the mid-point of the grid circuit of the tubes V₁V₂.

The invention is not limited to the precise arrangements shown for example. Although, for simplicity in drawing, triodes have been illustrated, other forms of tubes, e. g. pentodes, may be employed as may be desired.

What is claimed is:

1. In an amplifier system, a source of currents of carrier wave frequency to be amplified, a pair of electron discharge tubes each having electrodes including an anode, a cathode and control grid, a parallel tuned circuit coupled to said source and connecting the control grids of said tubes in push-pull relation, couplings of low impedance to said currents of carrier wave frequency coupling the anodes of said tubes to ground, a second parallel resonant circuit coupled between the cathodes of said tubes, neutralizing capacitors cross coupling the control grids and cathodes of said tubes, a second pair of tubes each having electrodes including an anode, a cathode and a control grid, an output circuit coupled between the anodes of said last named pair of tubes, connections coupling said last named parallel resonant circuit in push-pull relation to corresponding electrodes of said last named pair of tubes, a modulator circuit coupling the control grids of said last named pair of tubes in parallel, and neutralizing apparatus connected with the control grid of each of said last named tubes.

2. An amplifier system as recited in claim 1 wherein said corresponding electrodes are the control grids of said second named pair of tubes.

3. An amplifier system as recited in claim 1 wherein said corresponding electrodes are the cathodes of said second named pair of tubes.

4. In an amplifier system, a source of currents of carrier wave frequency to be amplified, a pair of electrode structures each including an anode, a cathode and a control grid, a parallel resonant circuit coupled to said source and connecting said control grids in push-pull relation, couplings of low impedance to said currents of carrier wave frequency coupling said anodes to ground, a second parallel resonant circuit coupled between said cathodes, neutralizing capacitors cross coupling said control grids and cathodes, a second pair of electrode structures each including an anode, a cathode and a control grid, an output circuit coupled between the anodes of said second pair of structures, connections coupling said second parallel resonant circuit in push-pull relation to corresponding electrodes of said second pair of structures, a modulator circuit coupling the control grids of said second pair of structures in parallel, and neutralizing apparatus connected with the control grid of each of said second structure.
